Primary Examiner — Karen S Acker(74) **Attorney, Agent, or Firm** — Mitchell Law PLLC;
Matthew W. Mitchell(57) **CLAIM**

The ornamental design for a fabric swatch, as shown and described.

DESCRIPTION

FIG. 1 is a front isometric view of the fabric swatch showing our new invention;

FIG. 2 is a front view thereof;

FIG. 3 is a rear view thereof;

FIG. 4 is a top plan view thereof, the bottom plan view being a mirror image thereof;

FIG. 5 is a right side view thereof, the left side view being a mirror image thereof; and,

FIG. 6 is an enlarged isometric view of area 6 circled within FIG. 1.

The broken lines on the outside edges of the drawings and the edges surrounding the recessed areas within the article depict portions of the fabric swatch that form no part of the claimed design. The broken line circumscribing the area labeled 6 within FIG. 1 and surrounding FIG. 6 indicate the area of the enlarged detail and form no part of the claimed design.
